UNITED STATES PATENT OFFICE.

BENJAMIN FRANKLIN, OF CHICAGO, ILLINOIS.

WINDOW-GUARD.

1,110,678.

Specification of Letters Patent. Patented Sept. 15, 1914.

Application filed April 10, 1914. Serial No. 830,902.

To all whom it may concern:

Be it known that I, BENJAMIN FRANKLIN, a citizen of the United States, and a resident of Chicago, in the county of Cook and State of Illinois, have invented certain new and useful Improvements in Window-Guards; and I do hereby declare that the following is a full, clear, and exact description thereof, reference being had to the accompanying drawings, and to the letters of reference marked thereon, which form a part of this specification.

This invention relates to window guards and consists of the matters hereinafter described and more particularly pointed out in the appended claims.

The object of the invention is to provide a guard for windows which may be readily and easily attached to a window and its associated casing, or which may be detached therefrom by one within the room in which the window is located when the window is closed, but which is securely locked in a position of security and safety when the window is open, no matter how small the opening; so that it cannot be removed either from a position inside or from a position outside of the window.

In the drawings:—Figure 1 is a view in elevation as looked at from the inside of a building, of a window casing or frame with the usual upper and lower window sashes thereof in a closed position, and with my improved window guard attached in proper position. Fig. 2 is a fragmentary view of the same in elevation on an enlarged scale illustrating the position the guard assumes when the lower window sash is in a raised position. Fig. 3 is a detail vertical section on an enlarged scale, the plane of the section being indicated by line 3—3 of Fig. 2. Fig. 4 is a detail perspective view of the upper left-hand corner of the lower window sash and its surroundings showing a part of the window guard, attached thereto. Fig. 5 is a detail perspective view of a channel which forms part of the attaching means for the window guard. Fig. 6 is a view in perspective of the guard as it appears when detached from the window. Fig. 7 is a detail plan sectional view, the plane of the section being indicated by line 7—7 of Fig. 4. Fig. 8 represents a view similar to that shown in Fig. 7 with the parts in changed relation.

Referring now in detail to that embodi-

ment of my invention illustrated in the accompanying drawings, 10 indicates a window casing or frame, and 11 the usual horizontal sill member forming a part thereof. 60 The said casing is provided with the usual upper and lower sash members 12 and 13 which are adapted for vertical sliding movement in suitable guides or runways forming a part of said casing.

14, 14 indicate vertically arranged channel members which are attached to the inner faces of the upright side members 13^a, 13^a of the lower window sash 13. Each of said channels 14, 14, are of a length approximating the vertical height of the upright member 13^a, 13^a of the window sash 13 and consists of a body member 14^a of U-shape in cross-section and having laterally extending flanges 14^b, 14^b which engage with the sash members 13^a, 13^a and by means of which said channels 14, 14, are fixed to said sash members. Each body member 14^a is provided with a slot 15 which extends approximately from top to bottom of said members, 70 is closed at both ends and has an enlarged hole 15^a at its upper end.

16, 16 indicate anchor plates fixed to the window sill 11. Said plates are arranged to cover laterally spaced recesses 17 formed in said sill, at a suitable distance from the plane of the lower sash 13. Said plates extend a short distance beyond the lateral edges of the recess 17 and are attached to said sill by means of screws 16^a, the upper surfaces of said plates being preferably made flush with the upper surface of said sill member 11. Each of said plates 16 has an aperture 16^b the purpose of which will appear as I proceed with my specification.

20 indicates as a whole my improved window guard (see Fig. 6) which is of a height and width approximating the height and width of the lower window sash 13. Said guard has an open frame which comprises, 100 as shown, upright side members 21, 21 and top and bottom horizontal members 22, 23. The frame is closed by a grating or other like device which is capable of freely admitting light and air while at the same time preventing the passage through the frame of persons or children from the inside or of burglars or thieves from the outside. In the drawings the frame 20 is shown as being closed by a grating made of upright laterally spaced bars 24 which are attached 105 at their ends to the top and bottom hori-

zontal members 22, 23 of the frame 20. To strengthen and brace the frame as a whole, a centrally disposed horizontal bar or member 25 is preferably so arranged as to bind the side members 21, 21 and the upright spaced bars 24 together. The window guard 20 is removably attached to the window sill 11 and to the lower sash member 13 in such a way that the lower sash may be raised freely as desired and when said sash is in raised position, the security of the guard is assured against removal either from inside or from outside the window. The preferred way of attaching said guard 20 is as follows: The bottom frame member 23 of the window guard is provided with depending, inwardly projecting, hook members 26. As shown in the drawings, the said hook members are formed by extending the lower ends 20 of two of the grating bars 24 below the horizontal bottom frame member 23 and bending the same inwardly to form hooks 26, 26, as illustrated in Fig. 6. The said hook members 26 are adapted to be inserted 25 into the apertures 16^b formed in the anchor-plates 16, fixed to the sill 11, so that when the window guard 20 is swung into an upright position, the said hooks lie within the recesses 17 formed in the sill 11. Said hooks 30 are made long enough so that when the guard rests upon the window sill, the hooked ends thereof will rest somewhat below the anchor-plates 16. The upper ends of the upright side frame members 21, 21 extend 35 beyond the upper surface of the horizontal top frame member 22 and are bent in a direction opposite to that of the hook members 26 to form outwardly extending horizontal hook members 27, 27. Each hook 40 member 27 is reduced in diameter near its free end to form a neck 28 and when said frame is in an upright operative position said neck 28 operatively engages within and has sliding bearing between the walls defining the lateral edges of the slot 15 formed in the channel member 14.

The window guard 20 is attached to a window sill provided with the anchor-plates 16 and a window sash provided with the channels 14, 14, in the following manner. The lower window sash 13 must be in its closed position and the frame 20 is then held in front of said sash with its upper end inclined toward the interior of the room. The bottom frame member 23 is then moved to bring its inner edge into engagement with the inner margin of the anchor-plates 16 (see Fig. 3) and when in this position the hook-members 26 are inserted into the apertures 16^b of said anchor-plates 16. The frame is then swung about the inner edge of the bottom frame member 23 as an axis, into a vertical position which movement brings the hooks 26, 26 within the recesses 17 formed in the window sill 11. The frame

is then in a position permitting a slight play in a vertical direction but cannot be withdrawn in that manner. When in a vertical position the bottom frame member 23 completely covers the plates 16, 16 in the sill. 70 With the window guard in this position the ends of the hook members 27, 27, engage that portion of the body member 14^a of the channel members 14 defining the lateral edges of the slots 15 adjacent the enlargements 15^a at the upper ends thereof. When in this position the said hook members cannot be inserted into the interior of the channel 75 14. The window guard is now slightly raised (the engagement of the hooks 26 with the anchor plate 16 permitting such movement) until the outer end of the hooks 27 are in alinement with the enlarged portions 15^a of the slots. A slight movement outwardly is then imparted to the upper end 80 of the guard to push the hooks 27 through said enlargements after which the guard is allowed to drop into place with the bottom frame member 23 resting upon the sill 11. The reduced neck portions 28 of the hooks 85 27 then engage within the slot 15. To remove the window guard, it is lifted vertically until the hooks 27 are in alinement with the enlargements 15^a of the slots 15 and the frame is then swung about its lower 90 edge as an axis when the hooks 26 may be disengaged from the apertures in the plate 16.

When it is desired to raise the lower sash 13 with the window guard 20 in place, said guard in no manner interferes therewith. The sash in rising carries with it its associated channels 14, 14 which channels will always be in position to guide and hold the end hook members 27 so that the guard cannot be withdrawn or removed when the sash is raised.

It is apparent that a window guard made in accordance with my invention can be readily and easily attached to or detached from the window sash and casing by a person from within the room and cannot be removed from the outside. This is advantageous inasmuch as the housewife can quickly detach the window guard for the purpose of washing windows or the like and replace the same when ready, without the necessity of manipulating catches, springs, or other devices, the operation of which she may not be familiar with. The guard rests close to 110 the window sash, is not in the way for the window curtains and does not present an unsightly appearance from the outside. The guard is always in a position of security and safety no matter how far the sash is raised 115 and the only time that said guard can be removed from the window to which it is attached is when said window is closed.

While in describing my invention, I have referred to certain details of mechanical con- 120

struction and arrangement, it is to be understood that the invention is not limited thereto, except as may be pointed out in the appended claims.

5 I claim as my invention:

1. A window guard adapted to be secured at the inside of a window comprising in combination with the window sill and the lower window sash, an open frame, a covering for the said frame, means for detachably engaging the bottom of said frame with said window sill, vertically extending guide members on said window sash, and devices at or near the upper end of said frame adapted 15 for locking and guiding engagement with said guide members.

2. A window guard adapted to be secured at the inside of a window comprising in combination with the window sill and the lower 20 window sash, an open frame, a grating covering said frame, apertured plates fixed to said

window sill, the said window sill being provided with recesses below said plates, means provided at the bottom of said frame for engagement in the apertures of said plates, 25 vertically extending slotted channel bars fixed to said sash, the slots in said channel bars being closed at their upper ends and being enlarged at said upper ends, and devices provided at the top of said guard 30 frame adapted for insertion through the enlarged upper ends of said slots and for locking and guiding engagement within said slots when said window sash is raised.

In testimony that I claim the foregoing as 35 my invention I affix my signature in the presence of two witnesses, this 7th day of April A. D. 1914.

BENJAMIN FRANKLIN.
